SEAT INSTALLATION

Le Grand S. Whedon and Albert A. Grinnell,
Medina, N. Y., assignors to Whedon, Inc.,
Medina, N. Y.

Application March 27, 1935, Serial No. 13,358

6 Claims. (Cl. 155—14)

This invention relates to an adjustable seat installation for vehicles or other structures, and it has particular relation to an improved supporting and operating mechanism for a seating structure wherein seat supporting members, seat back and seat bottom can be relatively moved to conform readily to various positions desired by persons having various heights, weights, or other characteristics that might require either average 5 or special seating arrangements.

The improved adjusting and supporting mechanism for adjustable seat structures to which the invention is directed involves an improvement over the type of seat structure disclosed in the 15 application of Albert E. Grinnell, Serial No. 694,819, filed Oct. 23, 1933, for seat construction, wherein an occupant while seated may adjust the elements of the seating structure to provide comfortable upright seating posture for the 20 back, or the seat may be so adjusted as to move the seat bottom with respect to its angular relation to the horizontal, in order to raise and lower portions thereof in conformity with the desired position or physical characteristics of various types of persons; or the seat bottom may 25 be moved bodily to various horizontal positions forwardly and rearwardly, while portions of the seat back can be adjusted forwardly and rearwardly at will, in addition to bodily movement 30 along with the movement of the seat bottom.

One of the principal features of the invention is exemplified in an improved structure of a controlling mechanism that is incorporated in a seat raising or lifting device that includes elements 35 for locking and unlocking the seat structure in any of its series of positions while the locking mechanism is substantially free from binding influences that might tend to interfere with uniform action of the mechanical parts of the structure.

Another feature of the invention resides in the construction of supporting links arranged in parallelism for supporting the seat at various horizontal positions and the cooperation of these elements with a locking device.

Another feature of the invention is exemplified in the combination of a substantially forwardly and rearwardly movable portion of the seating structure with devices which are operated to raise 50 or lower the seat within predetermined limits, and wherein mechanisms providing for these types of movements can be operated independently or concurrently as desired.

In the drawings:

Fig. 1 is a side elevation of the seating structure designed according to the invention;

Fig. 2 is a fragmentary vertical section taken substantially along the lines II—II of Fig. 3;

Fig. 3 is a fragmentary inverted or bottom plan 5 view with portions of the structure omitted;

Fig. 4 is a cross-section, on a larger scale, taken substantially along the lines IV—IV of Fig. 1; and

Fig. 5 is a cross-section, on a larger scale, 10 taken substantially along the lines V—V of Fig. 1.

In practicing the invention a seat structure 10 is installed upon a suitable support 12, which can be in the form of a vehicle floor, or the like, and includes supporting ears 13, rigidly secured 15 to the floor for pivotally supporting upon suitable bearings 15 a pair of lower frame members 16 in the form of channels that are spaced so as to be disposed on opposite sides of the seat structure.

Each of these channels opens upwardly and receives adjacent opposite ends thereof front and rear links 17 and 18, respectively, which are composed of flat bars 19 (Figs. 3 and 4) of relatively thin material. Opposite ends of each link 20 are spread apart to form pairs of fingers 20 and the lower fingers are secured by means of bolts 22 passing through them and through sides of the channels 16. The upper fingers 20 are secured by means of similar bolts 23 passing 30 through them and through the sides of a pair of upper frame members 25 in the form of channels which are parallel to the lower channels 16 and open downwardly.

Coiled torsion springs 26 are disposed between 35 the fingers 20 at each end of each of the links 17 and 18 and the ends 27 of each spring bear under the influence of tension in the spring coils against the adjacent fingers 20 and the bottom of the channel in which it is located. These torsion 40 springs constantly tend to move the links 17 and 18 in counter clockwise directions, as viewed in Fig. 2, about the bolts 22 and 23, and hence, tend to raise the channels 25.

As best shown in Fig. 3 the front and the rear links 17 and 18 are connected by transverse braces 29 and 30, respectively, which are integral 45 with the inner bar portions 19 of the links. One end portion on one side of each front link 17 is formed by bending one side of the brace at right 50 angles to its transverse portion, and similar constructions form the other end portion of the inner side of each link 18 and the other side of the brace. Each brace is formed of longitudinally divided tube forming material which has 55

- been crimped or otherwise formed into substantially tubular shape (Fig. 2) and flanged portions 32 thereof defining the longitudinal division are welded or otherwise secured together to provide a unitary rigid assembly. Thus forces applied to one of the front links are transmitted to the other and in the same manner the forces applied to either of the rear links are transmitted to the other. Sufficient clearance for the movement of the braces is provided by forming recesses 34a in the inner sides of the channels and thus when the braces are moved toward a horizontal position they do not strike the flanges of the lower channels.
- 15 An adjusting link 33 composed of flat bar pieces 34 is secured at its lower end by means of a bolt 35 in each lower channel 16 and its upper end is secured by means of a pin 36 in a downwardly opening channel slide 37 which is 20 slideable longitudinally in each upper channel 25 between the upper bolts 23. The downwardly extending walls 38 of the upper channel 25 are provided with inwardly turned guide flanges 40 which assist in guiding the slide and normally 25 maintain it against displacement from the channel. The links 33 are formed similarly to the front and rear links 17 and 18 previously described, but they are not provided with a transverse brace.
- 30 One of the upper corners of each channel 25 has a notch 42 cut therein and the channel slide 37 has a series of notches 45, one of which registers with the first notch 42, depending upon the 35 position of the slide as it is moved longitudinally in either of the upper channels. Locking fingers 46 formed upon arms 48 are carried rigidly upon a transverse rod 50 that extends from one upper channel 25 to the other and is journaled in bearing ears 52 struck out from the body of the channel. A lever handle 53 extending upwardly 40 as a rigid integral part of the rod 50 provides means for manually disengaging the finger 46 from the notches 42, 45. A torsion spring 55 coiled about the rod 50 has one end 56 connected to the rod and its other end 57 connected to the adjacent channel 25 and normally exerts 45 rotative force upon the rod to maintain the finger 46 in registering notches 42, 45.
- 50 A passenger seated upon the structure manipulates the handle 53 to release the adjusting slide 37 and if the seat is to be lowered, the weight of the passenger will force the seat downwardly until the links approach horizontal positions and the handle is then released. The finger 46 will 55 automatically snap into registering openings 42, 45. The passenger can raise the seat upon the links 17 and 18 by partially arising and permitting the seat bottom to follow upwardly under the influence of the several torsion springs 26 while maintaining the finger 46 disengaged from the notches 42, 45. At the desired elevation the handle is released and the slide 37 locked to maintain the channels 16 and 25 in rigid, locked 60 relation.
- 65 Since the locking slides 37 are located on both sides of the seat structure they provide a very rigid bracing action, and it is to be understood that the transverse braces 29 and 30 can be omitted in certain forms of the invention without unduly weakening the structure.
- 70 One end of a suspension link 60 is connected to each rear upper bolt 23 at each side of the seating structure and the other or upper end of the suspension link has a pivotal connection 62 75 securing it to the upper end portion of an up-

right standard 63 that is rigidly mounted, as indicated at 65 (Fig. 3), upon the rear portion of a frame 66 of a seat bottom 67. Each link 60 is bowed forwardly adjacent its lower end and provides for forward and rear swinging movement 5 of the seat bottom.

As best shown in Fig. 2, when the seat bottom is moved forwardly a greater portion of the link 60 is disposed substantially coextensively with the vertical standard 63, and hence, does not 10 project to the rear of the standard at locations above the seat bottom frame in any position of the parts of the structure. A conventional seat cushion 64 is mounted upon the frame 66.

Two U-shaped brackets 68 opening downwardly 15 are secured to the bottom of the seat frame 66 at locations spaced from the front extremity thereof and support rollers 69 that are mounted upon a transverse rod 70 extending rotatably through the brackets from one side of the seat 20 structure to the other. A handle 72 is provided upon one end of the rod and a pair of arms 73 rigidly carried by the rod adjacent opposite sides of the seat bottom are provided with locking fingers 75 normally engaging notches 76 formed 25 along the upper corner of each upper channel member 25.

The rollers are supported upon the upper surfaces of the channels 25 and in conjunction with the suspension links 60 provide for forward and 30 rearward movement of the seat bottom with respect to the channel members 25. The locking fingers 75 can be manipulated to permit this movement and to secure the members in adjusted positions.

One side wall extension 77 of each bracket 68 projects downwardly along the adjacent side of the channel 25 and is formed with an inwardly turned flange 78 which engages beneath the edge of the channel side and prevents the bracket from 40 being displaced vertically from the channel. The other side wall 79 of each bracket lies in sliding relation against the adjacent side of the channel 25 and the two bracket sides 77, 79 provide a guide for slidably receiving the front 45 portion of the channel 25. A torsion spring 80 coiled about the rod 70 has one end 82 connected to the rod and the other end 83 connected to the channel and constantly urges the locking finger 75 into engagement with one of the notches 50 76. Front end portions of the lower sides of the channels 25 are formed with lugs 85 which serve as stops to prevent the bracket 68 from slipping from the ends of the channels and the inwardly turned flanges 40 of the rear portions of the 55 channel also serve as stops to limit rearward movement of the brackets upon the channel. Thus the seat bottom can be adjusted forwardly and rearwardly upon the channels 25 and locked in various positions of adjustment by manipulating the lever 72 and exerting slight force in the direction desired upon the seat bottom.

When the seat bottom moves forwardly and rearwardly upon the rollers 69 and links 60 the pivotal connection 62 describes an arc, and hence, 65 the rear portion of the seat bottom is also slightly inclined with reference to the supporting channels 25 as the links and rollers approach the broken line position shown in Fig. 2. Sufficient play is provided in connecting the brackets 70 68 about the upper channels 25 to prevent binding of parts in assuming the position of inclination referred to.

At the rear portion of the seat bottom 67, a frame or shell 90 composed of metal or other 75

durable material is formed with side flanges 92, forwardly projecting lower arms 93, and back 95. Suitable pivotal connections 96, carried by the seat frame 66 at locations intermediate the forward and rearward portions of the seat bottom, pivotally support the forward ends of the arms 93 of the shell and provide for forward and rearward swinging action of the rear of the seat shell along a forward and upward arc from the rear of the seat bottom. A cushion 97, which is included with the shell 90 as a part of a seat back 98, is mounted in the seat shell in a conventional manner. Thus the seat back is bodily movable within predetermined limits about the pivotal connections 96.

An adjusting device 100 for the seat back is provided with brackets 102 bolted to the rear upper portion of the seat bottom frame 66 and a pivotal bolt 103 mounted thereon pivotally supports an upright bar 105 that has notches 106 formed in the forward edge thereof. The upper portion of the bar also has a slot 107 extending longitudinally therein. A coil spring 108 normally under compression surrounds the bar and has its lower end resting upon the brackets 103, while its upper end presses against the lower surface of a flange 109 that is a part of an angular bracket 110. Conventional fastening devices 112 secure the bracket 110 to an intermediate back frame portion 113 of the shell 90. The upper end portion of the bar 105 extends through a slot 115 (Fig. 3) formed in the flange 109 and any of the notches 106 can be engaged with the front edge wall of the slot 115 to lock the bar 105 to the bracket.

An actuating crank rod 116 rotatably mounted in an opening 117 of a flange 118 formed on the bracket 110 also rotatably extends through a flange 119 formed on a second bracket 120, and 40 is provided with a finger 122 of crank pin form. This finger fits slidably into the slot 107 of the bar 105 and is integral with a crank arm 123 of the rod. A handle or lever portion 125 of the crank rod 116 is adapted to be pressed downwardly to rotate the latter in the bearing brackets and thus to release the notches 106 of the bar 105 from engagement with the bracket 110. One 45 end portion of a spring 128 is connected, as indicated at 127, to the bracket 120 and its other end is connected, as indicated at 128, to the rod 116. This spring is normally under tension and 50 constantly exerts force in a clockwise direction upon the rod 116, as viewed in Figs. 1 and 2, for the purpose of maintaining the notched portion 55 of the bar locked with the bracket 110 and urges the bar toward the locked position as soon as the handle 125 has been released after pressing the latter downwardly.

The coil spring 108 is sufficiently strong to exert considerable force upon the seat back 98 tending to pivot it in an upward direction about the connections 96 and this action facilitates adjustment of the seat back. However, this spring is not sufficiently strong to interfere with the movement of the seat back to its rearmost position by pressure because the weight of a passenger seated in the vehicle overcomes the force of the spring. Since the pivotal action of the seat back is provided about the connections 96 at intermediate portions of the seat bottom, all portions of the seat back cushion 97, against which the passenger rests, are moved forwardly or rearwardly, as the case may be, in addition to the changing of the angle of inclination of the seat back, and as well as materially changing

the elevation of the upper end of the seat back. In the rearward position of the seat back, the rear portion of the seat bottom is disposed within the lower portion of the shell 90 between the sides of the shell. The links 60 and standards 63 are disposed adjacent the inner sides of the extensions 93 and are therefore substantially obscured from view.

One of the important advantages of this structure resides in the fact that a passenger seated in the vehicle can adjust the seat back without moving from the seat merely by operating the handle or lever 125 and then by leaning backwardly or forwardly, depending upon direction in which adjustment is desired. After the crank pin 122 has been actuated in the slot in the upper end of the bar 105 to disengage the notched portion of the bar from the bracket 110, the coil spring 108 causes the seat back to follow the passenger as he leans forward to the desired position, i. e., when the passenger desires to have the back adjusted forwardly. Since the pivotal connections 96 are disposed medially of the seat bottom, the rear portion of the seat bottom and the lower portion of the seat back substantially contact each other without materially separating during the pivotal movement of the back.

These conditions of operation are advantageous because the proper relationship between the seat back and seat bottom is retained regardless of the relative position of adjustment, and also the appearance of the seat structure as a whole is not marred by excessive separation of the junction portions of the cushions 64 and 97, which separation would occur if the pivotal connections for the shell 90 were located at the rear portion of the seat bottom.

In addition to the adjustment secured by the seat back structure just described, the forward and rearward adjustment provided by the suspension links 60 and rollers 69 upon the upper channels 25, together with the upward adjustment provided by the lifting links 17 and 18, insures the positioning of the seat back and seat bottom and the seating structure as a whole in any practical relationship conceivable. Although several phases of adjustment can be employed separately, each phase of adjustment can be employed to modify the seating characteristics of the others. 40 45 50

Although only one form of the invention has been shown and described in detail, it will be apparent to those skilled in the art that the invention is not so limited, but that various changes can be made therein without departing from the spirit of the invention or from the scope of the appended claims. 55

We claim:

1. In a seat supporting unit, a channel member having forward and rearward extremities, means for connecting the channel member to a seat bottom, a plurality of substantially parallel arms having upper end portions pivotally carrying the end portions of the channel member, supporting means for pivotally supporting the lower end portions of said arms, an adjusting device having an element slidably mounted in the channel member and an inherently rigid element pivotally connected thereto and to said supporting means, and means for selectively locking said slideable element in the channel member whereby the latter and the pivotal arms are locked in various relative positions to carry the channel member at various levels. 75

2. In a seat supporting unit, a channel member having forward and rearward extremities, means for connecting the channel member to a seat bottom, a plurality of substantially parallel arms having upper end portions pivotally carrying the end portions of the channel member, supporting means for pivotally supporting the lower end portions of said arms, a bar pivotally connected to said supporting means, a locking member 5 slidably mounted in the channel member and pivotally connected to said bar, said locking member and channel member having registerable recesses, and means connected to the channel member and 10 operable to engage in locking relation in the 15 registerable recesses.

3. In a seat supporting unit, a channel member having forward and rearward extremities, means for connecting the channel member to a seat bottom, a plurality of arms having upper end 20 portions pivotally carrying the end portions of the channel member and movable into collapsed relation substantially within the channeled portion of the channel member, supporting means for pivotally supporting the lower end portions 25 of said arms, an adjusting device connected to the channel member and to said supporting means for selectively locking the arms and channel member, torsion springs engaging the arms and their pivotal connections for constantly urging 30 all the arms in pivotal relation about the pivotal connections thereof.

4. A locking mechanism for seat structure comprising a channel member, a slide guided longitudinally in said channel member, a link 35 having one end portion pivoted to the slide, supporting means pivotally connected to the link at a location spaced from the slide, means for moving the channel member toward and away from said supporting means whereby the slide 40 moves in the channel member, locking mecha-

nism engageable with portions of the channel member and slide for selectively locking them in various positions of relative movement.

5. In a seat supporting unit, a channel member having forward and rearward extremities, means for connecting the channel member to a seat bottom, a plurality of downwardly extending arms having upper end portions pivotally carrying the end portions of the channel member, supporting means for pivotally supporting the lower end portions of said arms, an adjusting device 10 slideable in the channel portion of said member, means for pivotally connecting the adjusting device to said supporting means, said adjusting device including means for selectively locking said device in the channel member whereby the latter and pivotal arms are adjustable into various relative positions to carry the channel member at 15 various elevations.

6. In a seat supporting unit, a pair of substantially parallel downwardly opening upper channel members having forward and rearward extremities, means for supporting a seat bottom on said channel members, a plurality of downwardly extending arms having upper end portions carrying the forward and rear end portions of said channel members, supporting means pivotally connected to said lower end portions of said arms, a link pivotally connected to said supporting means, an adjusting member 20 slidably mounted in one of said upper channel members and pivotally connected to the link, said adjusting member and latter channel member having registerable recesses, and a rod extending rotatably through the latter upper channel member 25 and having an arm selectively engageable in locking 30 relation with the registerable recesses.

LE GRAND S. WHEDON.
ALBERT A. GRINNELL.
